15. Claims. (Cl. 62—119.5)

1

This invention relates to refrigeration, and is concerned with cooling subdivided compartments of a refrigerator with the aid of absorption refrigeration apparatus of the inert gas type having cooling elements operable at different temperatures.

It is an object of the invention to provide an improvement for cooling subdivided compartments of a household refrigerator with the aid of refrigeration apparatus of this type having cooling elements operable at different temperatures, particularly to effect more efficient cooling of the subdivided compartment which constitutes the freezing section of the refrigerator.

Another object of the invention is to provide an improved household refrigerator, having a cabinet space divided into a plurality of compartments which are cooled by cooling elements of absorption refrigeration apparatus of the inert gas type, in which better distribution of the cabinet space is obtained for cooling and maintaining food products at different temperatures in subdivided compartments therein.

This is accomplished by providing a plurality of cooling elements for cooling different subdivided compartments including a freezing compartment, and employing a partition having a low-temperature cooling element thermally associated therewith as the top wall or roof of the freezing compartment which may also serve as a supporting surface for food and other matter to be frozen.

The invention, together with the above and other objects and advantages thereof, will be more fully understood upon reference to the following description and accompanying drawings forming a part of this specification, and of which:

Fig. 1 more or less diagrammatically illustrates an absorption refrigeration system of the inert gas type embodying the invention;

Fig. 2 is a side vertical sectional view of a refrigerator with which is associated a refrigeration system generally like that shown in Fig. 1;

Fig. 3 is a front elevation, partly broken away and in section, of the refrigerator illustrated in Fig. 2, the front door or closure member being omitted to simplify the drawings.

Referring to Fig. 1, the invention is embodied in an absorption refrigeration system of a uniform pressure type in which an inert gas or pressure equalizing agent is employed. In a system of this type a refrigerant fluid, such as liquid ammonia, for example, is introduced into evap-

orator or cooling structure 14 from a condenser 15 in a manner which will be explained hereinafter. The refrigerant fluid evaporates and diffuses in cooling structure 14 into an inert gas, such as hydrogen, for example, to produce a refrigerating effect.

The resulting gas mixture of refrigerant and inert gas formed in the cooling structure 14 flows therefrom through a conduit 16, outer passage 17 of a gas heat exchanger 18 and vertical conduit 19 into an absorber comprising a vessel 20 and a looped coil 21. In the absorber vessel 20 and looped coil 21 refrigerant vapor is absorbed by a suitable absorbent, such as water, for example, which is introduced into the coil through a conduit 22. The hydrogen or inert gas, which is practically insoluble and weak in refrigerant, flows through an inner passage 23 of gas heat exchanger 18 and conduit 24 communicating with the cooling structure 14, as will be explained hereinafter.

From the vessel 20 enriched absorption liquid flows through a conduit 25 and an inner passage 26 of a liquid heat exchanger 27 into the lower end of a vapor liquid lift tube 28 of a generator unit 29. The generator or vapor expulsion unit 29 comprises a heating flue 30 having the vapor lift tube 28 and a boiler pipe 31 in heat conducting relation therewith, as by welding, for example. By heating flue 30, as by an electrical heating element or a gaseous or liquid fuel burner (not shown), liquid is raised by vapor lift action through tube 28 into the upper part of boiler pipe 31. The liberated refrigerant vapor entering boiler pipe 31 through tube 28, together with vapor expelled from solution in the pipe 31, flows upwardly into the condenser 15 which may be air-cooled and provided with heat dissipating members (not shown).

Refrigerant vapor is liquefied in the condenser 15 and such liquid returns to the cooling structure 14 to complete the refrigerating cycle, as will be explained presently. A pressure vessel 32 may be connected in any well known manner

to the condenser 15 and to a suitable part of the gas circuit. As shown, the pressure vessel 32 is connected by a conduit 33 to the outlet end of the condenser 15, and by a conduit 34 to the inner passage 23 of the gas heat exchanger 18.

In the boiler pipe 31 the weakened absorption liquid, from which refrigerant has been expelled, flows therefrom through a connection 35, outer passage 36 of liquid heat exchanger 27 and conduit 22 into the upper part of the absorber coil

21. The circulation of absorption liquid in the manner just described is effected by raising of liquid into the boiler pipe 31 through the vapor lift tube 28.

In accordance with this invention the cooling structure 14 comprises a low temperature cooling element 14a and a higher temperature cooling element 14b arranged to effect cooling of different compartments in a household refrigerator, the low temperature cooling element 14a being embodied in a horizontal partition or shelf which may be employed as a supporting surface for ice trays and the like and also serves as a top wall of a compartment adapted to receive frozen food packages and other matter to be frozen.

As diagrammatically shown in Fig. 1, the cooling elements 14a and 14b are in the form of looped coils which are disposed one above the other. The cooling elements 14a and 14b and parts immediately associated therewith are connected in the gas circuit in such manner that inert gas weak in refrigerant flows from the upper end of absorber coil 21 through inner passage 23 of the gas heat exchanger 18, conduit 24 and inner passage 37 of a second gas heat exchanger 38 into one end of cooling element 14a. After flowing through cooling element 14a, inert gas passes through a connection 39, outer passage 40 of gas heat exchanger 38 and conduit 41 into the upper end of cooling element 14b. The inert gas flows downwardly through cooling element 14b and passes therefrom through conduit 16 which, as previously explained, is connected to the outer passage 17 of gas heat exchanger 18 and through which inert gas rich in refrigerant flows to the absorber vessel 20.

Liquid refrigerant is supplied from condenser 15 through conduits 42 and 43 to cooling elements 14a and 14b, respectively. Refrigerant vapor flows successively through condenser sections 15a, 15b and 15c, some refrigerant vapor liquefying and condensing in the first condenser section 15a. Refrigerant vapor not liquefied in condenser section 15a passes into condenser section 15b and further condensation of refrigerant is effected therein. Liquid refrigerant passes from condenser section 15b through conduit 42 to cooling element 14a for flow through the latter. Refrigerant vapor not liquefied in condenser section 15b passes through conduit 44 to condenser section 15c in which condensation of refrigerant is effected. Liquid refrigerant passes from condenser section 15c through conduit 43 into the upper end of cooling element 14b.

In order to insure liquid refrigerant being supplied to cooling element 14b when air cooling of the condenser 15 is employed and the temperature of the air is relatively low, under which conditions there is a tendency for substantially all of the refrigerant vapor to be condensed in condenser sections 15a and 15b, a conduit 45 having a liquid trap formed therein is provided to divert liquid refrigerant from condenser section 15a into condenser section 15c.

As diagrammatically illustrated in Fig. 1, liquid flows in a downward path of flow in cooling element 14a in counterflow to inert gas which enters from the inner passage 37 of gas heat exchanger 38. On the other hand, liquid refrigerant supplied to cooling element 14b passes downwardly therethrough in parallel flow with inert gas. The cooling elements 14a and 14b are always in open communication with one another during operation of the refrigeration system and are operable at substantially the same pressure, that

is, the total pressure in the cooling elements 14a and 14b is substantially the same.

Since the inert gas flows successively through the cooling elements 14a and 14b, the gas in the cooling element 14a contains a lesser amount of refrigerant vapor than in the cooling element 14b. The partial vapor pressure of the refrigerant is a gradient, so that the temperature of liquid refrigerant in the cooling elements is also a gradient, the evaporating temperature of liquid being lower in the cooling element 14a which constitutes the freezing section of the cooling structure 14. In order to reduce and lower the mean or average temperature of cooling element 14a, the conduit 42 through which liquid refrigerant is supplied to that cooling element is arranged in thermal exchange relation with a part of cooling element 14b, as indicated at 46. Further, the conduit 42 is arranged in thermal exchange relation with the outer passage 40 of gas heat exchanger 38, as indicated at 47. In this manner relatively cool gas flowing through the higher temperature cooling element 14b is first utilized to abstract heat from liquid refrigerant in conduit 42, and subsequently cooler gas flowing through the gas heat exchanger passage 40 is utilized to abstract additional heat from such liquid refrigerant, thereby effectively precooling liquid refrigerant supplied to low temperature cooling element 14a.

By providing the second gas heat exchanger 38, inert gas weak in refrigerant and flowing to the low temperature cooling element 14a will be effectively precooled by cool gas passing from the low temperature cooling element to the higher temperature cooling element 14b. Such heat transfer from weak gas in gas heat exchanger passage 37 to cool gas in passage 40 decreases the mean or average temperature of cooling element 14a and increases the mean or average temperature of cooling element 14b, so that a wider temperature differential between the low and higher temperature cooling elements is effected.

Any unevaporated refrigerant passes from the lower end of cooling element 14b through a drain connection 48 into the conduit 42. Unevaporated refrigerant passes from the lower end of cooling element 14a into one leg of a U-shaped conduit 49 whose other leg is connected to the absorber vessel 20 at a region which is below the normal liquid level therein.

By providing conduit 45 to divert liquid refrigerant from the first condenser section 15a into the condenser section 15c, liquid refrigerant will be initially supplied to cooling element 14b when operation of the refrigeration system is started by applying heat to heating flue 30. This is necessary in order to start circulation of gas in the gas circuit since the low temperature cooling element 14a is located at a level between the upper end of absorber coil 21 and the liquid level in the absorber vessel 20. The circulation of gas in the gas circuit is effected by force developed within the refrigeration system and is due to the difference in specific weight of inert gas enriched in refrigerant vapor and passing downwardly through cooling element 14b to the absorber vessel 20, and that of inert gas weak in refrigerant vapor and passing upwardly from absorber coil 21 to the cooling structure 14. Since the column of gas rich in refrigerant vapor and passing from cooling element 14a to the absorber vessel 20 is heavier than the gas weak in refrigerant and passing upwardly from absorber coil 21 through the conduit 24, a force is developed within the

system for causing circulation of inert gas in the manner described. The force thus developed for circulating gas in the gas circuit is of sufficient magnitude to cause upward flow of gas partially enriched in refrigerant from cooling element 14a to cooling element 14b.

In order to simplify Fig. 1, the cooling structure 14 has been shown apart from a household refrigerator cabinet. One manner in which the cooling elements 14a and 14b of an absorption refrigeration system like that just described may be arranged in a thermally insulated interior of a household refrigerator cabinet in accord with the invention, for cooling separate compartments therein, is diagrammatically illustrated in Figs. 2 and 3. In Figs. 2 and 3 the cooling structure 14 is disposed in a cabinet 50 having a space 51 defined by an inner liner or shell 53 which is arranged to be supported within an outer metal shell 54 and insulated therefrom with any suitable insulating material 55. The space 51 is provided with a front access opening which is adapted to be closed by an insulated door 56 hinged to the front of the cabinet 50.

In order to position the cooling elements 14a and 14b in the space 51, the rear wall 57 of the cabinet 50 is formed with upper and lower openings 58 and 58a defined by rectangular frames 59 and 59a, respectively, which are formed of a material like wood, for example. Covers or closure members 60 and 60a containing insulating material 61 and 61a are provided for the openings 58 and 58a. The closure members 60 and 60a are arranged to bear against insulating gaskets 62, 63 and 62a, 63a, respectively, and removably secured to the rear wall 57 in any suitable manner (not shown).

The cabinet 50 is provided with a vertically extending apparatus compartment 64 at the rear thereof in which parts of the refrigeration system are housed, in a manner well known in the art. While only parts of the refrigeration system of Fig. 1 are seen in the compartment 64, it is to be understood that the system illustrated in Fig. 2 is generally like that of Fig. 1 with similar parts designated by the same reference numerals.

In Figs. 2 and 3 it will be seen that cooling element 14b associated with the upper closure member 60 is disposed within a metal shell or housing 65 which is fixed to and a unitary part of the closure member. The cooling element 14b comprises a looped coil having straight portions and connecting bends disposed essentially in a single vertical plane. The looped coil desirably is in good heat conducting contact with the housing 65, and this may be accomplished by dipping the shell and looped coil into molten zinc or other suitable corrosion protecting agent. As seen in Fig. 3, the looped coil may be in thermal contact with the top and side wall of the housing 65 and is out of direct physical contact with air in the space 51.

The cooling element 14a comprises a looped coil having straight portions and connecting bends disposed essentially in a single horizontal plane. This looped coil is disposed within and in good thermal contact with the top and bottom walls of a housing or shell 66 which extends from one side wall to the opposite side wall of the inner shell 53, and from the rear wall thereof to a region closely adjacent to the rear face of the door 56 when the latter is in its closed position. The housing 66 essentially serves as a horizontal partition to subdivide the space 51 into a bottom compartment 67 and a higher located compartment 68.

Since the bottom wall of the housing 66 forms the roof or ceiling of the bottom compartment 67 and the low temperature cooling element 14a is in good thermal contact therewith, an arrangement is provided for maintaining frozen food packages and other matter to be frozen at a low temperature in the bottom compartment which constitutes the freezing section of the refrigerator. This is so because air flowing in contact with the bottom wall of the housing 66 is cooled and flows downwardly to displace less cool air, thereby promoting natural circulation of air whereby a substantially uniform temperature in all regions of the bottom compartment 67 will be maintained and a steep vertical temperature gradient is avoided.

In the preferred embodiment of the invention shown and being described, the gas circuit of the refrigeration system lends itself to an arrangement which makes it possible to provide a freezing section or deep freeze compartment at the bottom of the cabinet space 51. Accordingly, the low temperature cooling element 14a is positioned at as low a level as possible with respect to the absorber vessel 20, as will be evident when reference is made to Figs. 1 and 2.

If desired, the freezing compartment 67 at the front access opening thereof may be provided with a closure member (not shown) which is hinged to the front of the housing 66 and spring-biased in any suitable manner to its closed position. Such a closure member effectively prevents air from the higher located compartment 68 entering the freezing compartment 67, whereby food products stored in the latter may be maintained at a desired low temperature. In place of such a closure member, the bottom wall of the housing 66 may have spaced apart guide members 69 fixed thereto adapted to slidably receive and support the flanges 70 to open top vessels 71, preferably formed of sheet metal, as shown in Figs. 2 and 3. Food products to be stored in the freezing compartment can be placed in the vessels 71, and, since the bottom wall of the housing serves as a cover for the open top vessels, a hinged closure member of the kind just described is not necessary for the freezing compartment 67. While the vessels 71 may be imperforate, openings may be provided in the side walls thereof when circulation of air through the vessels is desired, as indicated by dotted lines 72 in Fig. 2.

The top surface of the housing 66 is employed as a supporting surface upon which may be placed ice trays containing water for making ice cubes or other matter to be frozen. In order to thermally shield such matter from air in the higher located compartment 68, a protective hood 73 is provided at the top wall of the housing 66. The hood 73 may be formed of a plurality of layers 74 of thin aluminum sheeting, for example, having insulating air gaps therebetween. The individual layers 74 may be inverted U-shape in section, the opposing vertical arms or legs being adapted to rest on the top surface of the housing 66 at regions thereof closely adjacent to the side walls of the inner shell 53. By employing aluminum sheeting having bright reflecting surfaces for the layers 74, heat transfer by radiation from the compartment 68 to matter placed on the top surface of the housing is effectively retarded by the hood 73 which acts to re-radiate heat back to the compartment 68. The hood or radiation protector 73 may also be formed of layers of material having poor thermal conducting properties, which are coated with aluminum foil.

While the housing 65 of the higher temperature cooling element 14b is shown in Fig. 3 as being substantially midway between the side walls of the inner shell 53, it may be placed in any other position in the space 51. The housing 65 may be formed with a ledge 75 at a side wall thereof which is directly opposite one or more indented regions 76 in a side wall of the inner liner 53 for supporting a perforated shelf 77. Further, a shelf 78 may be provided substantially at the level of the bottom of the housing 65 which extends over the entire cross sectional area of the space 51. In such arrangement the housing 65 serves as a vertical partition between two compartments in the extreme upper part of the space 51. It may also be desirable in certain instances to employ a shelf 78 which is imperforate and formed of insulating material to provide three subdivided compartments 61, 68 and 79.

In view of the foregoing, it will now be understood that the housing 66 constitutes the first horizontally extending partition disposed above the bottom horizontal insulated wall defining the interior 51 of the cabinet 50. The horizontal partition formed by the housing 66 is spaced from the bottom horizontal insulated wall a distance less than half of the overall height of the cabinet interior 51 and defines the freezing section 67 in which the low temperature cooling element 14a is disposed closely adjacent to and in the immediate vicinity of such partition which serves as the roof or ceiling of the freezing compartment. The door 56 constitutes a single closure member at the front of the cabinet 50 for closing the front opening and gaining access to all parts of the cabinet interior 51.

While a single embodiment of the invention has been shown and described, it will be apparent to those skilled in the art that various changes and modifications may be made without departing from the spirit and scope of the invention, as pointed out in the following claims.

What is claimed is:

1. A refrigerator comprising a cabinet having the interior subdivided into compartments, absorption refrigeration apparatus having an inert gas circuit including an absorber and a low temperature cooling element and a higher temperature cooling element, said higher temperature cooling element being primarily effective to cool one compartment and said low temperature cooling element being primarily effective to cool another compartment which constitutes a freezing section, and structure including said low temperature cooling element which provides a top wall for said freezing section and also serves as a supporting surface upon which matter to be frozen may be placed, said low temperature cooling element being located at a level between the upper end of the absorber and the liquid level therein.

2. An absorption refrigeration system having an absorber and cooling structure comprising a low temperature cooling element and a higher temperature cooling element, means to supply liquid refrigerant to the upper ends of said cooling elements for gravity flow therethrough, means connecting said absorber and cooling structure to form a circuit for circulation of gas solely by force developed within the system due to difference in weight of columns of gas rich and weak, respectively, in refrigerant vapor, a circuit for absorption liquid including said absorber and a generator, said cooling structure being so connected and arranged in said gas circuit that said low temperature cooling element in its entirety

is disposed at a level between the upper part of said absorber and the liquid level in said absorption liquid circuit at the vicinity of said absorber.

3. An absorption refrigeration system as set forth in claim 2 including a connection for draining liquid by gravity from said low temperature cooling element to said absorption liquid circuit.

4. An absorption refrigeration system as set forth in claim 2 in which said means to supply liquid refrigerant to said cooling elements is so constructed and arranged that gas will always start circulating in one direction in said gas circuit when operation of the system is started.

5. A refrigerator comprising a cabinet having thermally insulated walls defining a space, absorption refrigeration apparatus having a gas circuit including a low temperature cooling element and a higher temperature cooling element which are always in open communication with one another and operable at substantially the same pressure, means to supply liquid refrigerant to said cooling elements, said higher temperature cooling element being arranged to abstract heat from the upper part of said space, and a horizontal partition in the bottom part of said space, said partition and thermally insulated walls defining a freezing compartment, said low temperature cooling element being vertically spaced from the bottom of said freezing compartment and disposed closely adjacent to and in the immediate vicinity of said partition which serves as the roof or ceiling of said freezing compartment.

6. A refrigerator as set forth in claim 5 in which said partition subdivides said space into said freezing compartment and a higher located compartment, and means for thermally shielding said partition from said higher located compartment.

7. A refrigerator comprising a cabinet having the interior thereof subdivided into compartments, absorption refrigeration apparatus having an inert gas circuit including a low temperature cooling element and a higher temperature cooling element which are always in open communication with one another and operable at substantially the same pressure, said higher temperature cooling element being at a higher level than said low temperature cooling element, means to supply refrigerant to said cooling elements, said higher temperature cooling element being primarily effective to abstract heat from one compartment and said low temperature cooling element being primarily effective to abstract heat from another compartment which constitutes a lower temperature section, and structure including said low temperature cooling element which provides the roof or uppermost horizontal wall for said lower temperature section and also serves as a supporting surface upon which ice trays and other matter to be frozen may be placed.

8. A refrigerator comprising a cabinet having the interior thereof subdivided into compartments, absorption refrigeration apparatus having an inert gas circuit including a low temperature cooling element and a higher temperature cooling element and condensing means for liquefying refrigerant vapor which is always in unobstructed communication with both of said cooling elements for delivering liquid refrigerant thereto, said higher temperature cooling element being primarily effective to cool one compartment and said low temperature cooling element being primarily effective to cool another compartment

which constitutes a lower temperature section, said higher temperature cooling element being above said low temperature cooling element, and structure including said low temperature cooling element which provides a top wall for said lower temperature section and also serves as a supporting surface upon which ice trays and other matter to be frozen may be placed, said condensing means being so constructed and arranged that liquid refrigerant is always initially supplied to said higher temperature cooling element when operation of the refrigeration apparatus is started.

9. An absorption refrigeration system having a circuit for inert gas including an absorber and cooling structure comprising a low temperature cooling element and a higher temperature cooling element, means to supply liquid refrigerant to said cooling elements, a circuit for absorption liquid including said absorber and a generator, said cooling structure being so connected and arranged in said gas circuit that said low temperature cooling element in its entirety is disposed at a level between the upper part of said absorber and the liquid level in said absorption liquid circuit at the vicinity of said absorber, and means for draining liquid from said higher temperature cooling element to said low temperature cooling element and for draining liquid from the latter to said absorption liquid circuit.

10. An absorption refrigeration system having a circuit for inert gas including an absorber and cooling structure comprising a low temperature cooling element and a higher temperature cooling element, means to supply liquid refrigerant to said cooling elements, the inert gas and liquid refrigerant flowing in the same direction in said higher temperature cooling element and in opposite directions in said low temperature cooling element, a circuit for absorption liquid including said absorber and a generator, said cooling structure being so connected and arranged in said gas circuit that said low temperature cooling element in its entirety is disposed at a level between the upper part of said absorber and the liquid level in said absorption liquid circuit at the vicinity of said absorber.

11. A refrigerator comprising a cabinet having thermally insulated walls defining a space, absorption refrigeration apparatus having a gas circuit including a low temperature cooling element and a higher temperature cooling element which are always in open communication with one another and operable at substantially the same pressure, means to supply liquid refrigerant to said cooling elements, said higher temperature cooling element being arranged to abstract heat from the upper part of said space, and a horizontal partition in the bottom part of said space, said partition and thermally insulated walls defining a lower temperature compartment in which said partition serves as the roof or ceiling of such compartment and provides a supporting surface for matter to be frozen, such surface being in good heat conducting relation with said low temperature cooling element.

12. A refrigerator comprising a cabinet having thermally insulated walls defining a space, absorption refrigeration apparatus having a gas circuit including a low temperature cooling element and a higher temperature cooling element which are always in open communication with one another and operable at substantially the same pressure, means to supply liquid refrigerant to said cooling elements, said higher temperature cool-

ing element being arranged to abstract heat from the upper part of said space, and a horizontal partition in the bottom part of said space, said partition and thermally insulated walls defining a lower temperature compartment in which said partition serves as the roof or ceiling of such compartment and provides a supporting surface for matter to be frozen, such surface being in good heat conducting relation with said low temperature cooling element, and means providing a horizontally extending wall above said supporting surface for thermally shielding matter on the latter from the region above such wall.

13. A refrigerator comprising a cabinet having the interior thereof subdivided into compartments, absorption refrigeration apparatus having an inert gas circuit including a low temperature cooling element and a higher temperature cooling element which are always in open communication with one another and operable at substantially the same pressure, means to supply refrigerant to said cooling elements, said higher temperature cooling element being effective to abstract heat from one compartment and said low temperature cooling element being effective to abstract heat from another compartment which constitutes a freezing section, structure including said low temperature cooling element which constitutes the roof or uppermost horizontal wall of said freezing section and also serves as a supporting surface upon which ice trays and other matter to be frozen may be placed, and means at the underside of said upper horizontal wall of said freezing section for removably supporting one or more vessels therefrom.

14. A refrigerator comprising a cabinet having the interior thereof subdivided into compartments, absorption refrigeration apparatus having an inert gas circuit including a low temperature cooling element and a high temperature cooling element which are always in open communication with one another and operable at substantially the same pressure, means to supply refrigerant to said cooling elements, said higher temperature cooling element being effective to abstract heat from one compartment and said low temperature cooling element being effective to abstract heat from another compartment which constitutes a freezing section, structure including said low temperature cooling element which constitutes the roof or uppermost horizontal wall of said freezing section and also serves as a supporting surface upon which ice trays and other matter to be frozen may be placed, and means including a protective hood for matter placed on the top surface of the upper horizontal wall of said freezing section for thermally shielding such matter.

15. In a refrigerator comprising a cabinet having thermally insulated walls defining the interior thereof provided with a front opening and refrigeration apparatus associated therewith including a first cooling element suitable for sharp freezing purposes and a second cooling element suitable for producing a higher temperature refrigerating effect, a horizontal partition in the interior of the cabinet which is the first such partition disposed above the lowermost or bottom horizontal thermally insulated wall defining the interior of the cabinet, a single closure member for closing the opening and gaining access to all parts of the cabinet interior, said first horizontal partition being spaced from said lowermost horizontal wall a distance less than half of the overall height of the interior of the cabinet and de-

fining the freezing section of the latter, said second cooling element comprising piping in the cabinet interior which is located above said first partition, structure forming a housing which is disposed in the cabinet interior and envelops the piping of said second cooling element, said housing including metal sheeting having said piping in thermal contact therewith, and said first partition embodying said first cooling element and providing a good heat conductive path from the latter to the top surface of said first partition upon which can be placed matter to be frozen.
